[57] CLAIM

The ornamental design for a cat scratching post, as
shown and described.

DESCRIPTION

FIG. 1 is a perspective view of a cat scratching post and
base showing my new design;

FIG. 2 is an end elevational view thereof with the
opposing end view being substantially a mirror image
thereof;

FIG. 3 is a side elevational view thereof with the opposing
side view being substantially a mirror image thereof;
and,

FIG. 4 is a top plan view thereof.

The bottom of the design is substantially plain and unor-
namented.

FIG.1

FIG.2

FIG.3
